UNITED STATES PATENT OFFICE.

LAWRENCE R. PEEPLES, OF SHAWNEETOWN, ILLINOIS.

WIRE-FASTENER.

No. 869,458.

Specification of Letters Patent.

Patented Oct. 29, 1907.

Application filed January 9, 1907. Serial No. 351,508.

To all whom it may concern:

Be it known that I, LAWRENCE R. PEEPLES, a citizen of the United States, residing at Shawneetown, in the county of Gallatin, State of Illinois, have invented 5 certain new and useful Improvements in Wire-Fasteners; and I do hereby declare the following to be a full, clear, and exact description of the invention, such as will enable others skilled in the art to which it appertains to make and use the same.

10 This invention has relation to means for securing the longitudinal or other wires of a fence to the fence-post.

Heretofore, it has been common to "staple" the wires of a fence to its posts when the latter were composed of wood that permitted this to be done. In the 15 case of cement or metallic posts it has been usual to permanently secure the wire-fastening means in the post, or at least permanently secure the means in the post to which the wire-fastening means are connected.

It is the object of my invention to provide improvements whereby both the keys which secure the wires of the fence to the posts as well as the pin which engages and connects the keys with the posts may be removable, in order to impart greater range of usefulness to the post and the wire-fastening means, and 25 secure the ends of economy as well.

The nature of the invention is embodied in the devices portrayed in the annexed drawings, forming a part of this specification, in view of which it will be fully described with respect to its construction and 30 mode of operation, and then be pointed out in the subjoined claims.

Of the said drawings—Figure 1 is a front view of the fence post having my improvements applied thereto in which the longitudinal wires of the fence run in the 35 plane of the front face of the post. Fig. 2 is a horizontal section taken in the plane 2 2, Fig. 1. Fig. 3 is a perspective view of a post in which the fence wires run as in Fig. 1, but in which the key or fastening wires pass cornerwise through the post from one side to an adjacent side. Fig. 4 is a horizontal section of Fig. 3. Fig. 40 5 is a side view of a fence post in which the wires are maintained in connection therewith as shown in Fig. 1. Fig. 6 is a sectional view of the same, the course of the keys or fastening device through the post being shown in 45 dotted lines. Fig. 7 is an elevation of the pin or rod by which the keys or wire fasteners are secured in the posts. Figs. 8 and 9 are perspective views of different forms of keys or wire fastening means that may be employed in the invention.

50 Similar numerals of reference designate similar parts or features, as the case may be, wherever they occur.

My improvements are particularly applicable to cement posts and hence the post represented in the drawings may be supposed to be of this character though 55 it will appear obvious that the improvements may be

applied to posts composed of iron or other material as well as cement posts.

Having reference to the drawings for more particular explanation of the invention 11 indicates a fence post which may be, as shown in Fig. 1, of a rectangular form 60 in cross section provided centrally and longitudinally with a hole 12 into and through which from the top the pin 13 may be inserted, said pin having on its upper end a conical cap 14 to shed rain or water from entering the holes and also a wire loop or handle 15 by 65 which the pin may be taken hold of and withdrawn from the hole 12. Intersecting the said vertical hole 12 from the face of the post are numerous holes 16 which may run horizontally as shown in Figs. 1 and 2, or in inclined direction downward as shown in Fig. 7. 70

17 designates what, for the purposes of this specification I term a "key" for fastening the wires to the post, which key consists of a bar of metal having a flattened inner end 18 provided with an eye 19 of a diameter sufficient for the pin 13 to extend therethrough, 75 and having a hook 20 or other suitable wire-engaging means on its outer end. Instead of flattening the entire inner end of the key, as just described the said inner end may be made round, as at 18' with a flattened or otherwise formed part at a proper point so as to have 80 an eye 19' formed through it. In all cases the key will be provided with detachable wire-engaging means on its front end, and an eye will be formed through its rear end for the reception of the pin. The latter is a means for detachably securing the keys in a fence-post, while 85 the key itself detachably engages the wires of the fence.

In the employment of my invention, as already intimated, I may form a hole longitudinally and centrally in the post 11, and make as many transverse holes 16 90 therein as may be desired from the front face inward intersecting the said vertical holes, and in some cases passing beyond it. I then proceed to connect the uppermost wire of the fence with the hook 20 of the key 17, when the shank of the key will be inserted in the hole 16 of the post until the eye 19 comes into alignment with the vertical hole when the point of the pin will be passed through the said eye, securing the key and its attached fence wire to the post. I proceed in this manner from the top to bottom until all of the wires are secured to the post and until the pin 13 is fully inserted in the vertical hole and its cap 14 rests on top of the post. 95

When it is desired to detach the wires, the pin will be withdrawn and all of the keys 17 released by being simply unhooked from the wires and the parts disposed 100 of as desired.

In some instances the holes 16 for the keys may be made cornerwise through the post as shown in Fig. 3 in which case the outer ends of said holes will be arranged on a central longitudinal line on the front face 110

of the post and extend diagonally through said post to either of the said sides so that when the keys 17 are placed in the holes as before stated with the fence wires secured to the hooks 20 the eyes 19 of said keys will 5 project beyond the said adjacent side of the post sufficiently far for the pin 13 to enter them as shown in Figs. 3 and 4 in which case the longitudinal wires of the fence will be bound to the post as before stated with reference to Figs. 1 and 2 and the pin and keys will be 10 rendered removable and detachable from the wires as before stated.

In another instance the holes 16 may extend through the post from the front to the rear side as shown in Figs. 5 and 6 in which case the keys will be inserted through 15 from the front face of the post to and beyond the rear thereof so that the eyes of the rear of the post will be in vertical alinement to receive the pin 13 and confine them therein in the same way as previously set forth.

Instead of extending the holes on horizontal lines in 20 the posts as represented in Fig. 2 they may in all cases be arranged in downward inclined direction as indicated in Fig. 5 so that any water entering said holes will run down out of the same and not stand therein to rust or injure the keys. It is intended, however, to

make the keys as well as the pin of galvanized iron so 25 as far as possible to prevent corrosion. In all instances whatever the form of the keys and pin 13 as well as the holes through the post may take, it is proposed to make both the keys and the pin removable so that when it is desired to take down the fence the work can be readily 30 accomplished and the pin and keys taken out of the post and the former detached from the fence wires so as to be reusable in the setting of a new fence.

What is claimed is—

1. Means for detachably engaging the wires of a fence 35 to a fence post, consisting of a key comprising a straight bar adapted to be inserted in the holes of a post, and having a hook on its forward end to detachably engage the wire of a fence and provided on its opposite end with an eye, and a pin removably engaged with said eye.
2. The combination, with a fence-post provided with 40 holes for the reception of removable keys having hooks on their outer ends to detachably engage the wires of a fence, and provided on their opposite ends with eyes and a pin removably engaged with said eyes.

Intestimony whereof, I affix my signature, in presence of two witnesses.

LAWRENCE R. PEEPLES.
